UNITED STATES PATENT OFFICE.

LAUREL MILO HOYT, OF HILLSBORO, OREGON.

RIMLESS-EYEGLASS MOUNTING.

No. 895,566.

Specification of Letters Patent.

Patented Aug. 11, 1908.

Application filed November 4, 1907. Serial No. 400,676.

To all whom it may concern:

Be it known that I, LAUREL MILO HOYT, a citizen of the United States, residing at Hillsboro, in the county of Washington and State of Oregon, have invented certain new and useful Improvements in Rimless-Eyeglass Mountings; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to improvements in rimless eye-glass mountings and has for its object to provide a mounting which while extremely light presents a particularly strong and rigid construction.

20 With this object in view my invention consists in providing the strap which engages the periphery of the eye-glass with an upper and a lower reinforcing brace in such manner that the strap and glass are held rigidly in position and will not become wabbly.

25 Referring to the accompanying drawing: Figure 1 is an elevation showing a pair of eye-glasses illustrating the application of my invention, and Fig. 2 is a perspective view 30 of strap and brace on a greatly enlarged scale.

Like numerals of reference indicate the same parts throughout the several figures in which:

1 indicates the glasses and 2 the mounting. 35 The mounting comprises the usual spring bridge 3 and the strap 4, said strap 4 being provided with a post 5. Connected to the post 5 at the inner end thereof is an upper brace 6 and a lower brace 7, said braces 6 and 40 7 extending to the outer ends of the strap 4 and being connected thereto as clearly shown in the drawing. By this construction the parts can be, if desired, much lighter than is the usual custom, thereby saving material, 45 while at the same time the construction presents a strong rigid mounting.

As is evident from Fig. 2 the arc of the strap 4 can be adjusted to conform to glasses of different sizes by slightly bending the 50 braces 6 inwardly or outwardly.

Having thus described my invention what I claim as new and desire to secure by Letters Patent of the United States, is,—

An eye-glass mounting of the character de- 55 scribed, comprising a strap for engagement with the periphery of an eye-glass, a post for said strap and an upper and a lower brace extending from the ends of said strap to the inner end of said post, substantially as de- 60 scribed.

In testimony whereof, I affix my signature, in presence of two witnesses.

LAUREL MILO HOYT.
